UNITED STATES PATENT OFFICE.

ALONSON D. PERKINS, OF SAN FRANCISCO, CALIFORNIA.

MEANS TO PREVENT THE UNAUTHORIZED USE OF EXPLOSIVE-ENGINES.

1,116,324.

Specification of Letters Patent.

Patented Nov. 3, 1914.

Application filed August 25, 1913. Serial No. 786,477.

To all whom it may concern:

Be it known that I, ALONSON D. PERKINS, a citizen of the United States, residing at San Francisco, in the county of San Francisco and State of California, have invented a new and useful Means to Prevent the Unauthorized Use of Explosion-Engines, of which the following is a specification in such full and clear terms as will enable 10 those skilled in the art to construct and use the same.

This invention relates to a device for the purpose of preventing the unauthorized use of explosion engines, and an object thereof 15 is to provide means whereby an unauthorized person attempting to operate an explosion engine such as is commonly used in automobiles, etc., will set off an alarm which he cannot stop, and at the same time cut out 20 the ignition system so that the engine cannot be further operated.

Another object of the invention is to provide means whereby the gasoline supply may be cut off from the engine at the same 25 time the alarm is set, thus adding an additional check to the operation of the motor.

A further object of the invention is to provide means whereby the alarm will be set off and the engine prevented from operating 30 whether an attempt is made to start the engine on the magneto or the battery, it being common to provide engines with two systems of ignition, but which systems form no part of the present invention.

35 An embodiment of the invention is shown in the drawing in which the same reference numeral is applied to the same portion throughout, but I am aware that there are many modifications thereof.

40 Figure 1 is a plan view of a portion of the frame of an automobile having an explosion engine mounted thereon to which is applied this alarm, Fig. 2 is a view looking toward the rear of the car of the switch for setting 45 the alarm and the pitman for cutting off the gasoline supply when the alarm is set, the gasoline valve being turned at 90 degrees to the position it occupies in Fig. 1 for convenience of illustration, Fig. 3 is a view of 50 the alarm setting lock looking toward the front of the car, Fig. 4 is a view of the alarm setting switch, the alarm relay and the alarm bell as they appear mounted on the front of the dashboard of the car, Fig. 5 is 55 a view looking toward the end of the relay

in the direction of the arrow on Fig. 4, the dash-board being shown in section, Fig. 6 is a view of the grounding device of the relay circuit for setting off the alarm when the engine shaft is turned off preparatory to 60 starting the car, and Fig. 7 is a diagrammatic view illustrating a common form of dual system wiring to which wiring this alarm system is applied.

The numeral 1 represents the side frames 65 of an automobile, 2 the front axle, 3 the front wheels, 4 the steering arms and 5 the link joining said arms together. The side frames are suitably connected together by means of cross braces 7 for the support of 70 the engine 8, while immediately at the rear of the engine is the dash-board 9. The engine is of a common form having two sets of cylinders 10 and 11, the engine frame supporting the usual fan 12 immediately at the 75 rear of the radiator 13. Installed at one side of the engine is the steering post 14 for the operation of directing the car, while installed at the other side of the engine is the magneto 15, said magneto being driven in a 80 well known manner from the shaft 16 passing into the gear casing 17, which form of drive is well known in the art.

Mounted upon the front of the dash-board is a bell 19, a relay box 20 and the 85 alarm setting lock 21, the latter extending through the dash-board in order to enable the user to apply his key thereto in locking and unlocking the same. The lock barrel is 90 installed in a cylindrical shell 23 and is rotated by means of the handle 24, the key being inserted in the opening 25 to enable the lock barrel to be shifted from one position to another. It is contemplated that any 95 form of lock and key may be used. At the front of the dash-board the lock barrel 22 is 100 provided with a pin 25 and with a cam 26. The pin 25 has a pitman 27 pivoted thereto, which pitman in turn is connected to the stem 28 of the gasoline cut off valve 29, pipes 30 and 31 extending respectively to the gasoline supply tank and the carbureter. The stem 28 passes through a suitable bracket 32 to cause it to move properly.

The alarm 19 consists of a common form 105 of gong 33, hammer 34 and cover box 35, within which are installed the customary operating magnets.

The relay mounted upon the front of the 110 dash-board comprises a base plate 40 and

secured in place by means of screw brackets 41 and 42 is the box 20 within which is a double electromagnet 43. Pivoted above the magnet 43 is a suitable armature 44, which 5 is held away from the magnet 43 by means of a suitable spring 45, said spring being connected with the base plate 40. Mounted at one end of the base plate 40 are three spring contacts 46, 47 and 48, said contacts 10 being suitably insulated from each other and the base plate by means of fiber blocks 50 supporting them. The central spring contact 47 has a projecting lip 51 which strikes a contact point 52 for a purpose to be 15 described. On the lower part of the plate 40 is a fiber block 53 which block supports binding posts 54, 55, 56 and 57.

The armature 44 carries a small fiber finger 60 which is adapted to bear on the inclined end 61 of the spring contact 46 to bring all of the contacts 46, 47 and 48 together when the magnet 43 is energized, while at the same time the projection 51 is disconnected from the contact 52. The contact 46 has a wire 61' extending to the binding post 54', while from the binding post 54 a wire 62 extends to the magnet 43 and a wire 64 extends from the other side of said magnet to the binding post 57. Extending 25 from the central spring contact 47 is a wire 65 extending to the binding post 56, and extending from the outer spring contact 48 to the binding post 55 is a wire 66.

Secured on the lower portion of the dash- 35 board in a place convenient to the crank shaft 67 is a spring contact plate 68, said plate being close enough to said shaft to be touched by the pin 69 when said shaft is rotated, said pin grounding said contact 68 40 and completing the alarm circuit as will be later explained.

Fig. 7 illustrates diagrammatically a well known ignition system and magneto making use of two sets of spark plugs for the operation of the engine. In this diagram 15 indicates the magneto, 19 the alarm bell, 67 the shaft, 43 the relay magnets, 44 the relay armature, and 46, 47 and 48 the spring contacts.

The numeral 70 indicates the common switch for starting and stopping the operation of the ignition system, 71 indicates the spark coil, B a suitable battery, and 22 the device for setting the alarm.

Extending above the magneto are two sets 55 of wires as indicated to the first set of spark plugs and to the second set of spark plugs, while extending from the magneto to the coil are the wires 80 and 81. Also connected with the magneto and coil are the high tension wires 82 and 83, while another high tension wire 84 extends from the terminal wire 82 to the top of the binding post on the breaker box 85. Extending from the binding post 86 is a high tension wire 87 60 which extends to the binding post 88 at the

side of the breaker box, another wire 89 extending from there to the dash-switch 70, from which latter point a ground wire 90 extends to the frame.

It will be observed the high tension wires 70 are all indicated with heavy lines while the low tension wires are otherwise shown.

The battery B has a ground wire 91 and a wire 92 leading to the coil 71, while from the central terminal of the coil a wire 93 75 leads to the contact point 52 and from there through the central spring contact 47 to the ground wire 47'. Connected with the wire 92 is a wire 94 which extends to one of the spring contacts adjacent the cam 26, while 80 from the other spring contact adjacent the cam 26 a wire 95 extends to one of the binding posts of the alarm 19. From the other binding post of the alarm 19 a wire 96 extends to the spring contact 48.

85

Extending from one of the terminals of the magnet 43 is a wire 97 which is connected with the binding post at the spring contact 68 adjacent the engine shaft 67, while extending from the other side of the 90 magnet 43 is a wire 98, which is connected with the wire 95. Connected with the spring contact 46 is a wire 99 which extends to the high tension wire 82, and in order to maintain the wire 97 grounded after the 95 pin 69 has left the spring contact 68 a wire 100 is provided, which wire is brought into contact with the spring contact 48 when the magnet is energized.

The operation of the apparatus is as follows: It will be assumed that the car has been stopped and the switch 70 opened in the usual manner, whereupon the person operating the engine will remove his key from the lock barrel 22, but in order to remove the 100 key therefrom it is necessary to turn the same to the position indicated in Fig. 2 with the cam 26 making a connection between the wires 94 and 95, whereupon the alarm will be set and will cause the magnet 43 to become energized should a person turn the engine shaft 67 over without having the key to the lock barrel 22, no attempt being made 110 to prevent the proper operation of the switch 70. Should the engine be turned over 115 a circuit will be completed through the wire 91, battery B, wire 92, wire 94, wire 95, wire 98, magnets 43 and wire 97 to the ground, the engine shaft, thus energizing the magnet 43 and causing the armature 44 120 to be depressed whereupon the wire 96 will be grounded through the wire 47', the contact point 52 will be removed from contact with the ground wire 47' and the three spring contacts will be brought together and 125 in contact with the wire 100, so that circuits will then be complete independent of the movement of the engine shaft through the wire 91, battery B, wire 92, wire 94, wire 95, alarm 19, wire 96, spring contact 48, 130

spring contact 47 and wire 47' to the ground, as well as through the then formed shunt circuit including the wire 98, magnets 43, wire 97, wire 100 and contacts 48, 47 and 5 wire 47' to the ground. The result of this will be that the battery circuit will be cut off from the coil 71 by being broken at the point 52 so that the high tension side of the coil will not deliver a spark at the spark 10 plugs, and in the same way because of the grounding of the wire 99 it will be impossible for the magneto to make a circuit at the other side of the spark plugs and in addition the gasoline valve will at this same 15 time be closed, thus reducing the possible amount of gasoline which might by any contingency be used to that quantity actually in the carburetor.

It will be seen from the foregoing that 20 whether an attempt is made to start the engine with the battery or with the magneto, that in either event will the alarm be set off and both ignition systems will be prevented from operating should the person 25 attempting to operate the car fail to disconnect the wires 95 and 94 by the proper rotation of the cam 26.

Having thus described my invention what 30 I claim as new and desire to secure by Letters Patent of the United States, is as follows, modifications within the scope of the 35 claims being expressly reserved:

1. Means for preventing the unauthorized use of explosion engines, comprising the 40 combination with the ignition system of an explosion engine, of an alarm, manual means for setting said alarm, means to set off said alarm thus set when the engine shaft is rotated, and means to prevent the operation 45 of the ignition circuit only during the time said alarm is operating.

2. Means for preventing the unauthorized use of explosion engines, comprising the combination with the ignition system of 45 an explosion engine, of an alarm, manual means for setting said alarm, an electrical circuit for setting off said alarm thus set when the engine shaft is rotated, and means to prevent the operation of the ignition 50 circuits during the time the alarm is operating.

3. Means to prevent the unauthorized use of explosion engines, comprising the combination with the ignition system of an explosion engine, of an alarm, means for setting said alarm, electrical circuits for setting off said alarm thus set when the engine shaft is rotated, other electrical circuits to maintain said alarm in operation independent of the circuit closed by the engine shaft when the alarm has been set off, and means to prevent the operation of the ignition circuits when the alarm is operating.

4. Means for preventing the unauthorized 65 use of explosion engines, comprising the com-

bination with the ignition system of an explosion engine, of an alarm, manual means for setting said alarm, means to set off said alarm thus set when the engine shaft is rotated, means to prevent the operation of the ignition circuit only during the time said alarm is operating, a fuel supply pipe, and means to cut off the fuel supply on the setting of the alarm.

5. Means for preventing the unauthorized use of explosion engines, comprising the combination with the ignition system of an explosion engine, of an alarm, manual means for setting said alarm, an electrical circuit for setting off said alarm thus set when the engine shaft is rotated, means to prevent the operation of the ignition circuits during the time the alarm is operating, a fuel supply pipe, and means to cut off the fuel supply on the setting of the alarm. 85

6. Means for preventing the unauthorized use of explosion engines, comprising the combination with the ignition system of an explosion engine, of an alarm, means for setting said alarm, electrical circuits for setting off the alarm thus set when the engine shaft is rotated, other electrical circuits to maintain said alarm in operation independent of the circuit closed by the engine shaft when the alarm has been set off, means to prevent the operation of the ignition circuits when the alarm is operating, a fuel supply pipe, and means to cut off the fuel supply on the setting of the alarm. 90

7. Means for preventing the unauthorized use of explosion engines, comprising the combination with the ignition system of an explosion engine, including a battery and a magneto, of an alarm, manual means for setting said alarm, means to set off said alarm thus set when the engine shaft is rotated, and means to ground the magneto circuit and to break the battery circuit upon the setting off of the alarm. 100

8. Means for preventing the unauthorized use of explosion engines, comprising the combination with the ignition system of an explosion engine, including a magneto and a battery, of an alarm, means for setting said alarm, an electrical circuit for setting off said alarm thus set when the engine shaft is rotated, a fuel supply pipe, means to cut off the fuel supply on the setting of the alarm, and means to ground the magneto circuit and to break the battery circuit 115 upon the setting off of said alarm. 120

9. Means for preventing the unauthorized use of explosion engines, comprising the combination with the ignition system of an explosion engine, including a battery and a magneto, of an alarm, a setting device, an electrical circuit extending to said setting device and adapted to be closed to set off the alarm thus set when the engine shaft is rotated, other electrical circuits to maintain 125 130 135 140 145 150 155 160 165 170 175 180

said alarm in operation independent of the circuit closed by the engine shaft when the alarm is set off, and means to ground the magneto circuit and to break the battery circuit during the time said alarm is in operation.

In testimony whereof I have hereunto set

my hand this 16th day of August A. D. 1913, in the presence of two subscribed witnesses.
